United States Patent Office

Des. 206,792
Patented Jan. 31, 1967

206,792

SHOE DAUBER

Lewis James Halberstadt, Williamsburg, Mass., assignor
to Pro-Phy-Lac-Tic Brush Company, Florence, Mass., a corporation of Delaware

Filed Mar. 10, 1966, Ser. No. 1,395

Term of patent 14 years

(Cl. D9—2)

FIG. 1 is a side elevational view of a shoe dauber, showing my new design;

FIG. 2 is a top plan view of the shoe dauber shown in FIG. 1;

FIG. 3 is an end view of the shoe dauber shown in FIG. 1; and

FIG. 4 is a perspective view of the shoe dauber shown in FIG. 1.

I claim:

The ornamental design for shoe dauber, as shown and described.
